REFRIGERATOR DOOR RELEASE

Philip S. McLean, Bloomfield, N. J., assignor to Westinghouse Electric & Manufacturing Company, East Pittsburgh, Pa., a corporation of Pennsylvania

Application January 21, 1933, Serial No. 652,840

8 Claims. (Cl. 292—254)

The objects of this invention are to provide a simple and practical device for releasing the lock of a refrigerator door and one which can be operated by simple knee pressure or the like; 5 also to provide a releasing device of this character of compact inexpensive form, which can be readily applied to existing boxes and without marring or in any way spoiling the appearance of the same.

These objects and others are attained by the novel features of construction, combinations and relations of parts hereinafter disclosed and broadly covered in the claims.

The drawings accompanying and forming part 15 of the specification illustrate several of the various possible embodiments of the invention, it being understood that the actual physical form may be varied to suit different conditions, within the true and intended scope of the invention.

Fig. 1 is a front view of a refrigerator having a form of the invention applied thereto.

Figs. 2 and 3 are enlarged fragmentary front and plan views respectively of the lock mechanism and the releasing device.

Fig. 4 is a view looking in the direction of the arrow 4 in Fig. 2 and showing in particular the swinging bolt releasing lever hung directly from the keeper element of the lock.

Figs. 5, 6 and 7 are detail views of a modification, Fig. 5 being a broken part sectional view similar to Fig. 4, Fig. 6 a top plan and Fig. 7 a sectional detail as on line 7—7 of Fig. 5. Figs. 8 and 9 are broken front and side views of another form of the invention.

The box indicated at 9 in Fig. 1 may be considered as typical, having a swinging door or doors 10, held closed by a lock consisting generally of a sliding bolt 11, cooperating with a keeper 12. Ordinarily, such a lock is released 40 by hand by means of a suitable handle 13. The operation of such a handle often times is inconvenient, particularly with the hands full as frequently is the case in carrying objects to the refrigerator.

The present invention consists of a conveniently located device, which can be actuated by knee or body pressure to force back the tip of the bolt over the hook or shoulder of the keeper. This releasing device consists, in the forms of 50 the invention shown, of a knee lever 14, hung

from a pivot screw stud 15, in position immediately in front of the roller 16, pivoted at 26, at the tip of the locking bolt.

In the several illustrations, the releasing lever is mounted directly on the keeper, in the first 55 form Figs. 1 to 4, by providing a stud or projection 17 on the upper portion of the mounting plate 18 of the keeper receiving the shouldered pivot screw stud 15, which forms the pivot for the lever; in the second form, Figs. 5 to 7, by 60 providing the upper portion of the hollow keeper body 19 with an extension 20, receiving the pivot collar 21 on the upper end of the lever and holding the pivot screw 15 for the same and in the third form, Figs. 8 and 9, by setting the 65 pivotal portion of the lever in a slot or cavity 30 in the nose of the keeper, with the angular extension 31 of the lever reaching in under the roll on the end of the lock bolt.

In the first forms shown, the upper and lower 70 edges of the hollow keeper are notched as indicated at 22, to let the release lever drop back clear of the bolt roller, so as not to interfere with the movement of the bolt to its maximum door holding position and so as to permit the lever being 75 freely swung outwardly to release the bolt.

The last mentioned features will be clear from Figs. 2 and 3, where it will be seen that the pivot for the releasing lever is set back approximately 80 to the vertical center of the keeper base plate, so that the lever in its normal hanging position will have a tendency to rest against the inner ends of the notches 22, leaving clear space at 23, between the lever and the roll when the bolt is fully extended back of the hook or inside cam face 24 of 85 the keeper. Thus when the door is slammed, the bolt can project to its maximum holding position without any interference from the releasing lever.

The lever is shown as made of rod material 90 providing a rounded surface for engagement with the rounded surface of the roller, thus reducing friction between the two and enabling the one to have a camming action over the other. This camming action is favored as will be clear from Fig. 95 3, by the travel of the roller 16, down over the incline of the cam face 24 of the keeper and in such movement also as the roller moves down the cam face 24 and hence travels outwardly away from the box, the round face of the lever will gradually 100

pass around in back of roller 16, tending thereby to thrust it outward in a door opening direction, as well as simply repressing the same. This cam action of the lever may be increased or diminished 5 by varying the position and shape of the lever. By setting it further back or towards the box, the tendency to shift the bolt in a door opening direction is increased. Ordinarily, it is sufficient to make the bolt releasing lever with a substantial- 10 ly straight portion 25, Fig. 2, substantially parallel and approximately in line with the center of the roll, as in the illustration.

The bolt roller on being forced back to the tip of the keeper point, as in dotted lines Fig. 3, then 15 engages the outer incline or cam face 33, enabling the bolt spring to react and swing the door open, aided usually by expansion of the rubber or other packing 27, forming the seal between the door and box face.

20 As a consequence, only a relatively light force is required, just sufficient to carry the center of the roll beyond the point of the keeper, the door then swinging open under the combined push of the bolt against the outer cam face and 25 the expansion of the door packing. As such a light force is all that is required, the lower end of the lever may be finished off simply with a loop or turn 28, positioned for convenient engagement by the knee, elbow, or other part of the body. The 30 outward bend provided in the rod at 29, is to give the handle end of the lever sufficient offset from the box to be free of the door as the latter swings open.

By modifying to some extent the shape and 35 position of the parts, the invention may be adapted to different makes of boxes. Also, since the releasing device fully unlocks the door, the invention makes it practical to dispense with the usual door opening handle, simplifying and reducing 40 the cost of the lock to that extent. The latter feature has been illustrated in Figs. 8 and 9, where the locking bolt is indicated in the form of a vertically swinging spring pressed lever adapted to ride up over the nose of the keeper, and 45 drop down behind the locking shoulder of the same and where the releasing lever constitutes the sole means for unlatching the door.

The releasing of the bolt is effected in this invention by a simple pushing movement of the 50 knee or other part of the body and can be effected without reaching around or standing in front of the door, thus leaving the door unimpeded and clear to swing freely open. The movement of the releasing device is in direct opposition to 55 the engaging movement of the bolt and keeper and so the release of one from the other is effected smoothly and easily and in a line to directly assist in the opening of the door. The releasing handle, if desired, may be extended lower or be extended 60 upwardly, as for operation by the elbow or the like. While the lever is usually so designed as to drop back by gravity clear of the bolt movement, it will be evident that a spring may be provided to insure this bolt clearing action of the 65 lever and such a spring is indicated by way of example at 32, in Fig. 7.

What is claimed is:

1. A releasing device for a refrigerator door lock of the type in which a locking bolt rides up over the inclined nose and drops down behind an inclined shoulder of a keeper and comprising a bolt releasing lever pivotally hung from the keeper in position with one portion of the same disposed to lie beneath the bolt in its locked 75 engagement with the keeper and a dependent

handle portion hanging from the keeper in position for convenient actuation by knee pressure or the like, the nose portion of the keeper structure being slotted to accommodate the bolt engaging portion of the bolt releasing lever and said portion of the bolt releasing lever being received and housed within said slotted nose portion of the keeper.

80

2. A releasing device for a refrigerator door lock of the type in which a movable bolt on the door carries a roller to roll over an incline and engage behind a retaining shoulder of a keeper on the box structure and comprising a bolt releasing lever pivotally hung on the box structure in position with a portion of said lever disposed in front of the bolt carried roller when the latter is engaged behind the retaining shoulder and thereby in relation by direct engagement with the roller to roll the same in reverse direction back over the retaining shoulder to the aforementioned incline of the keeper and said releasing lever having a dependent swinging handle portion exposed at the face of the box structure in position for direct actuation by knee pressure or the like.

85

3. A releasing device for a refrigerator door lock of the type in which a movable bolt on the door rides over an incline and engages behind an abrupt retaining shoulder of a keeper on the box structure and comprising a bolt releasing lever hung to swing in front of the bolt in the engaged position of the latter with the retaining shoulder and having a movement in a plane to force the bolt back over the retaining shoulder to the incline leading thereto, said bolt releasing lever having a pendant handle portion exposed and projecting over the face of the box in position for direct knee operation or the like.

90

4. A releasing device for a refrigerator door lock of the type in which a keeper mounted in 115 exposed relation on the face of the box structure has a hollow to receive a cooperating movable bolt on the door structure and comprising a bolt releasing lever pivotally suspended directly from said keeper in position with a portion 120 of the same intercepting the hollow of the keeper to thereby stand in position to directly engage the bolt when the latter is engaged with the keeper and said lever terminating in a handle portion projecting from said bolt releasing portion and positioned by the exposed keeper structure in exposed relation over the face of the box structure for convenient operation by knee pressure or the like.

100

5. A releasing device for a refrigerator door lock of the type in which a movable bolt on the door cooperates with a hollow portion of a keeper on the box structure and comprising a bolt releasing lever pivoted to swing across the hollow of the keeper in the bolt releasing direction 130 to thereby directly engage and force back the bolt when engaged with the keeper and said bolt releasing lever having an extended leverage handle projecting in exposed relation at the face of the box structure in position for convenient knee 135 operation or the like.

105

6. A releasing device for a refrigerator door latch of the type involving cooperating bolt and keeper members on the door and box structures and comprising a bolt releasing lever pivotally 145 hung from the keeper member on an axis substantially at right angles to the face of the box structure and movable in a substantially parallel plane across the face of the box structure to force back the bolt member and said lever hanging down 150

in said free swinging relation over the face of the box structure in position to be actuated by knee pressure applied laterally across the face of the box structure.

- 5 7. A releasing device operable by knee pressure and comprising a substantially vertically disposed lever pivotally hung at its upper end in cooperative relation to a keeper and having an extension projecting angularly inwardly from
10 said point of pivotal support to lift a latch bolt free of the keeper and said lever extending down-

wardly from said point of pivotal support to within reach of the knee of a user.

8. A releasing device operable by knee pressure and comprising a lever pivotally hung in cooperative relation to a keeper and means associated with the lever for lifting a latch bolt free of the keeper, said lever extending from said pivotal support to within the reach of the knee of a user. 80
